OTHER PUBLICATIONS

Commonly assigned co-pending U.S. Appl. No. 29/875,620, filed May 8, 2023, entitled Tire.

(Continued)

Primary Examiner — George D. Kirschbaum

(74) *Attorney, Agent, or Firm* — Gardner, Linn, Burkhardt & Ondersma LLP

(57) **CLAIM**

The ornamental design for a tire, as shown and described.

DESCRIPTION

FIG. 1 is a front, right and top side perspective view of a tire showing the new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings represent portions of the tire that form no part of the claimed design.

1 Claim, 8 Drawing Sheets
